UNITED STATES PATENT OFFICE.

HENRY O. COOPER, OF COLUMBIA, SOUTH CAROLINA.

FOLDING-CHECK-BOOK HOLDER.

Application filed April 10, 1926. Serial No. 101,197.

This invention relates to a holder for folding check books, and has more particular reference to a device adapted for attachment to a folding check book and shiftable relative to the latter so as to be positionable for retaining the check book in an open condition.

It is well known that considerable difficulty and inconvenience is experienced in filling out the checks of a folding check book by reason of the fact that such check books tend to return to folded condition and must be manually prevented from doing so while a check of the book is being filled out.

The primary object of the present invention is to provide an improved device adapted for attachment to a folding check book and shiftable thereon so as to be positionable for effectively retaining the book in open or unfolded condition so that the user of the book will experience no difficulty or inconvenience in filling out a check of the book.

A further object is to provide a check book holder of the above kind shiftable relative to the book for permitting folding of the same and embodying means to engage the folded portion of the check book for retaining the latter in compactly folded condition when not in use.

A still further object is to provide a check book holder of the above kind which is extremely simple and durable in construction as well as efficient in operation.

Other objects will become apparent as the nature of the invention is better understood, and the same consists in the novel form, combination and arrangement of parts hereinafter more fully described, shown in the accompanying drawing and claimed.

In the drawing, wherein like reference characters indicate corresponding parts throughout the several views,

Figure 1 is an inverted perspective view of a check book equipped with a holder constructed in accordance with the present invention, the check book being retained in folded condition by the holder;

Figure 2 is a transverse sectional view taken upon line 2—2 of Figure 1;

Figure 3 is a longitudinal section taken upon line 3—3 of Figure 2;

Figure 4 is a transverse section taken upon line 4—4 of Figure 3;

Figure 5 is a fragmentary top plan view of the device shown in Figure 1; and

Figure 6 is a fragmentary perspective view of the holder removed from the check book.

Referring more in detail to the drawings, 5 indicates a conventional form of folding check book, the back and checks of which are folded upon a transverse line intermediate their ends as at 6, whereby the book normally assumes a folded condition for convenience in carrying the same in the pocket of the user. The present invention aims to provide a device adapted for attachment to a folding check book of this kind, and shiftable relative to the same so as to be positionable for releasably retaining the check book in unfolded or open position, and for this purpose the invention embodies a slide attachable to and movable longitudinally on the check book. This slide preferably consists of a flat plate 7 of comparatively stiff or rigid form and of a size to extend across the back of the check book, the ends of the plate 7 being provided with upwardly projecting flanges 8 adapted to engage the longitudinal edges of the check book and having inwardly extending lips 9 upon the ends of said flanges 8 adapted to engage the margin of the uppermost check of the book whereby the device is slidably retained upon the check book. The lips 9 are spaced from the plate 7 a distance substantially equal to the thickness of the unfolded check book when in original condition with none of the checks removed, so that the checks will be maintained in flat contiguous relation when the slide is applied to the book.

It is thus apparent that if the check book is opened or unfolded and the slide moved longitudinally of the book from the position of Figure 1 to a position wherein the same extends to opposite sides of the fold 6 of the book, the latter will be effectively retained in flat open condition whereby the uppermost check of the book may be readily filled out without the expenditure of manual effort in retaining the check book open, and so that little difficulty or inconvenience is experienced by the user of the book. When the book is no longer required for use, the slide may be 100 shifted to the stub end of the check book so that the latter may readily return to its folded condition, and in order to retain the book in compactly folded condition when the slide is so shifted, the intermediate portions 105 of the flanges 8 are extended above the lips 9 and provided with inwardly directed

110

flanges 10 adapted to engage the folded end portion of the check book whereby the latter is prevented from swinging to a partly open position unless the same is manually withdrawn from beneath the flanges 10.

An upwardly bowed leaf spring 11 is attached at one end to the upper surface of the slide plate 7 so that the spring is disposed between the plate and the back of the check book. This spring 11 compensates for reduction of the thickness of the check book as checks are detached therefrom whereby the slide is effectively retained in engagement with the book and the checks maintained in compact relation until all of the checks are used and removed. Obviously, when the device is placed upon a full book of checks, the spring 11 will be flexed to substantially flat form, and as the checks are removed, the spring will automatically tend to return to its bowed condition for forcing the plate 7 away from the back of the check book and maintaining the lips 9 in tight engagement with the uppermost check of those remaining. The present device is preferably constructed from light metal having sufficient stiffness to withstand ordinary strain, and in order to reduce the weight of the device to a minimum, portions of the plate 7 may be removed as indicated at 12.

Obviously, suitable advertising matter may be placed upon the exposed surface of the plate 7 if desired.

From the foregoing description it is believed that the construction and operation as well as the advantages of the present invention will be readily understood and appreciated by those skilled in the art.

Minor changes may be made without de-

parting from the spirit and scope of the invention as claimed.

What I claim as new is:—

1. A holder of the character described comprising a plate adapted to extend across the back of the folding check book and provided with end flanges projecting upwardly for positioning at the longitudinal edges of the check book, and inwardly extending lips upon the ends of said flanges arranged to engage the marginal portions of the uppermost check of the check book when in unfolded condition, whereby the holder may be slid longitudinally on the check book for positioning so as to project at opposite sides of the fold line of the book and thereby maintain the latter in unfolded condition, said flanges having intermediate portions projecting upwardly beyond the lips and provided with inwardly directed flanges arranged to engage the folded portion of the check book when in folded condition. 45 50 55 60

2. A folding check book holder of the character described, comprising a plate body designed to position across the back of said book, a flange formed across each of two opposite edges of said plate and designed to overlie adjacent edges of the check book, and a plurality of inwardly directed lips formed at the free edge of each of said flanges, said lips on each flange being divided into two portions lying in different planes, one thereof being designed to engage over the checks in the book at all times, the other being designed to receive the free end 70 75 of the checks when the checks are in folded condition.

In testimony whereof I affix my signature.

HENRY O. COOPER.
